TRAVERSE CARRIAGE KNOCK-OFF MECHANISM

John E. Lovely, Springfield, Vt., assignor to Jones & Lamson Machine Company, Springfield, Vt., a corporation of Vermont

Application August 26, 1935, Serial No. 37,887

15 Claims.

(Cl. 82—21)

It has been usual practice heretofore when chasing threads on a turret lathe or the like, to automatically unclutch the driving connections to the lead screw at the desired limit of traverse and then to release the nut by hand.

In accordance with this invention, however, mechanism is provided for automatically disconnecting the nut from the lead screw when the desired length of work has been operated upon.

10 This eliminates the necessity of the additional hand operation heretofore required.

It is often desirable to provide for a feed of the saddle or carriage by means other than the lead screw, as, for example, by a rack and pinion, either the lead screw or other means being usable selectively. An automatic knock-off for one such other feed means is shown in my Patent No. 2,006,144 granted June 25, 1935.

A further object of this invention, therefore, is to associate this lead screw disconnecting mechanism with such other feed knock-off, so that any type of carriage feed may be employed at will, certain actuating mechanism being common to all.

25 For a more complete understanding of this invention, reference may be had to the accompanying drawings in which—

Figure 1 is a fragmentary front elevation of a mechanism embodying this invention.

30 Figures 2, 3 and 4 are detail sections on the correspondingly numbered section lines of Figure 1.

Figure 5 is a perspective view of a cam member.

Figure 6 is a fragmentary front elevation to a 35 smaller scale than Figure 1 and showing a rack and pinion knock-off mechanism.

Figure 7 is a left end elevation of the mechanism shown in Figure 6, the lathe ways being shown in section.

40 Referring first to Figures 1 and 4, at 1 is indicated the lead shaft of a turret lathe or similar machine, to which shaft is secured, as shown in Figure 4, a hollow lead screw 2. This lead screw, as shown, is provided with a head 3 provided 45 with suitable means well known in the art for securing the lead screw and lead shaft together. This lead screw is rotatable within a sleeve 4 forming part of the tool carriage of the machine, this sleeve 4 being shown as provided with 50 a casing portion 5 integral therewith, this casing having an upper wall member 6 from which extend spaced side wall members 7 and 8, which are partly closed off at their outer ends by the aligned spaced wall portions 9 and 10, respectively. Between the wall portions 7 and 8 is fulcrumed

without capability of lateral play, as on the pivot bolt 12, a lever 15. This lever 15 is provided with a transverse perforation 16 internally threaded for a portion of its length, as at 18. Mating the threads of this perforation are 5 threads of a sleeve 19 through which extends the shank 20, carrying on its inner end a nut segment 21 in position to mate the threads of the lead screw 2. The inner plane end 22 of the sleeve 19 engages against the back face of the 10 segment 21. The sleeve 19 fills the space between the back face of the segment 21, and a washer 25 secured to the rear end of the shank 20, as by means of a screw, the head of which is shown at 26. The threaded sleeve 19 may be provided 15 with a polygonal head 27 to facilitate engagement by a wrench so that the sleeves 19 and 22 can be adjusted in or out in the perforation 16, thus to insure proper engagement of the nut segment with the lead screw when the lever is in 20 its operatively engaged position, as will later appear. Means, such as a set screw 29, bearing on a plug 30 may be employed to lock the sleeve 19 in any adjusted position.

The free end of the lever 15 has extended there- 25 through a sleeve 35 having a counterbored por- tion 36. Slidable through this sleeve is a latch element 37 having a head 38 riding in the counterbored portion 36 of the sleeve 35. A coil spring 39 seated in this counterbored portion 30 bears on the base of this portion and the head 38, and normally presses the latch end 40 of the element 37 into position to engage within a socket member 41 secured as by threading, as at 42, through the wall portion 8. This socket 35 member 41 comprises a plug having a central perforation 43, the outer end of which serves to receive the latch portion 40 and which also has slidably therein a latch release pin 45. This release pin has an enlarged diameter portion 46 40 terminating in a head 47. A coil spring 48 re- acts between the base of the enlarged portion 46 and the base of a counterbored portion 49 in the plug 41 and normally holds the inner end of the release pin 45 retracted sufficiently beneath the inner end of the plug 41 to permit latching en- 45 gagement therewith of the latch element 40, but by exerting inward pressure against the head 47 the release pin 45 may be pressed inwardly suffi- 50 ciently to retract the latch and release it from its engagement in the perforation 43. The weight of the lever 15 and the parts carried there- by bias the lever to swing the segment 21 out of engagement with the lead screw 2 and thus in- 55 terrupt the driving traverse connections between

the lead screw and the tool carriage. A pin 58 passing through the head 51 of the plug 41 and through a slot 52 through the portion 46, serves to limit the amplitude of motion of the release pin 45 and to hold the release pin in assembled relation within the perforation 43.

Means are provided for automatically actuating the release pin to force the latch into inoperative position and allow the disconnection of the nut segment from the lead screw when the traversing carriage approaches the desired limit of motion. This means, as shown, comprises an adjustable fixed stop 60 carried by a suitable part 61 of the machine bed and shown as provided at its outer 10 end with an abutment screw 62, which may be secured in adjusted position in the end of the stop, as by means of a lock nut 63. The tool carriage has mounted for movement therein in its direction of traverse a slide member 65, which 15 may be provided with a screw abutment 66 adjustable by turning, and in position to impinge against the head of the stop screw 62, thus to stop further traverse of the slide 65 while the tool carriage continues its motion sufficiently to operate the latch release mechanism to disconnect 20 the nut segment 21 from the lead screw. The mechanism by which this latch is disconnected 25 will now be described.

The slide member 65, as shown best in Figure 30 1, is provided with a pull rod 78 threaded at its inner end into the slide 65, and having a necked portion 71 terminating in a head 72. This head 35 may be provided with a perforation 73 for the reception of a suitable bar by which the pull rod 40 may be turned to adjust the extent to which the head 72 projects from the face of the member 65. Arranged to engage over this pull rod at the neck 71 is a bar 75, shown best in Figure 3 as provided with a slot 76 at one edge, through which 45 the neck portion 71 may pass, this slot being of such a size that the inner beveled end of the head 72 may impinge on the marginal portions thereof, which are beveled as at 77. The bar 75 is secured, as by screws 78, to a lever 80, fulcrumed 50 on the pin 81 which is held between a pair of jaws 82 projecting from a supporting bracket 83 rockable on the plug 41. A handle 830 secured at its inner end to the bracket 83 facilitates turning of the bracket about the axis of the latch and release pins to bring the bar 75 into or out of 55 cooperative relation to the pull rod 78. This lever 80 carries at one end a pin 84 provided with a head 85 positioned opposite to the head 41 of the latch release pin 45. The spring 48, pressing 60 the release pin 45 outwardly against the lever 80, holds the beveled surface of the left hand face of the bar 75 in engagement with the beveled portion 77 which coacts as a latch mechanism to hold the bracket 83 in the operative rocked position shown, though by pressing down on the 65 handle 830 the lever 80 may be rocked against the action of the spring 48 sufficiently to disengage the bar 75 from the rod 78 so that the bracket 83 may be swung forward and downward to render 70 the knock-off inoperative when desired. As the traversing carriage continues its motion to the left, as shown in Figure 1, after the screw 88 has struck the screw 62 and the traversing motion of the member 65 has been stopped, the head 72 75 of the pull rod engaging on the marginal portion 71 of the bar 75, rocks this bar and the lever 80 about the fulcrum 81 and presses the latch release pin inwardly until the latch is moved out of latching relation to the member 41, whereupon 80 the lever 15 carrying the nut segment 21 drops

away from the lead screw 2 and thus operatively disconnects the traversing carriage from the lead screw. A threaded stop element 89 carried by the member 83 prevents undue rocking motion of the lever 80 in the opposite direction. Besides this automatic means for releasing the latch mechanism, means are provided for releasing it by hand. This means comprises a handle 90 which extends out from the casing 5 between the confronting faces of the wall members 8 and 10. Its inner end is forked so that the branches 91 and 92 engage on opposite sides of the lever 15, and they are pivotally mounted on the sleeve 35 within which the latch member 37 moves. The branch 91 carries a pair of cam follower projections 93 which ride on the inner face of a cam member 94, shown detached in Figure 5. This cam member is provided on its inner face with a pair of recesses 95, one side 97 of each of which is inclined and provides a cam surface for engagement with the corresponding follower 93. This cam 94 is pinned to the latch bar 37 as by the pin 98, which passes through diametrically arranged slots 99 in the sleeve 35. The handle 90 is normally held in angular relation to the lever 15 shown in Figure 2, this being accomplished by means of a plug 100 seated in a socket 101 in the lever 15 and backed up by a coil spring 102, the outer end of this plug bearing on a hardened head 103 of an element 104 inserted into the handle 30 member 90 between the branches 91 and 92. An end wall portion 106 on the lever 15, engaging the handle 90 between the branches 91 and 92, serves as a stop to limit the upward rocking of the handle as pressed by the spring pressed plug 100, and a lower inclined wall portion 107 on the lever 15 acts as a stop to limit the downward rocking motion of the handle when it is pressed downwardly by hand against the pressure of the spring pressed plug 100. In the normal upward position of the 40 handle the cam followers 93 rest in the deeper portions of the recesses 95 so that the latch member 37 may be pressed outwardly to its limit of motion in position to latch into the member 41. Upon downward rocking of the handle 90, however, the branch 91 is turned about the axis of the sleeve 35 to an extent sufficient to bring the cam follower 93 against the inclined faces 97 of these recesses sufficiently to force the cam 94 outwardly and with it the latch 37 to retract this 50 latch from operative condition so that the lever 15 may swing downwardly and remove the nut segment 21 from engagement with the lead screw 2.

In Figures 6 and 7 the lead screw knock-off 55 mechanism is shown as employed in connection with a knock-off mechanism of the type shown in my Patent No. 2,006,144, to which reference has been made, either driving traversing arrangement, the lead screw or rack and pinion, being 60 employed at will but with certain common knock-off actuating parts. The slide member 65 herein illustrated is the spool 160 of the patent, which, when it moves against the fixed stop, and the carriage continues its movement, causes 65 release of the latch pin at 125, which may have previously held the handle 126, corresponding to the handle 180 of the patent, in elevated position with the rack 127 and pinion 128 feed in operative condition, thus to disconnect this feed. 70 When it is desired to employ the rack and pinion feed, the handle 80 will be depressed to disconnect the lead screw segment, and the handle 830 may be depressed also to disconnect the bar 75 from the pull rod 78, and the handle 126 will 75

be raised to render the rack and pinion feed effective. When the handle 126 is depressed and the handles 90 and 830 are in their upper positions, the lead screw feeding mechanism is operative and the rack and pinion feed inoperative.

5 From the foregoing description of one embodiment of this invention, it should be evident to those skilled in the art that various changes and modifications might be made without departing 10 from the spirit or scope of this invention as defined by the appended claims.

I claim:

1. In combination, a traversing carriage, a rotary lead screw, a nut segment carried by said carriage and movable into and out of engagement with said screw and biased out of such engagement, a latch for holding said segment in engagement with said screw, a fixed stop, a member movably carried by said carriage and engageable with said stop as said carriage approaches a desired traverse limit to be stopped while the motion of said carriage continues, and means actuated by the further motion of said carriage after the motion of said member with said carriage has been stopped to release said latch.

2. In combination, a traversing carriage, a rotary lead screw, a nut segment carried by said carriage and movable into and out of engagement with said screw and biased out of such engagement, a latch for holding said segment in engagement with said screw, a fixed stop, a member movably carried by said carriage and engageable with said stop as said carriage approaches a desired traverse limit to be stopped while the motion of said carriage continues, means actuated by the further motion of said carriage after the motion of said member with said carriage has been stopped to release said latch, and means actuated to move said latch-releasing means into and out of operative positions.

3. In combination, a traversing carriage, a rotary lead screw, a lever fulcrumed on an axis substantially parallel to said lead screw and held against motion axially thereof, a nut segment carried by said lever for engagement with said lead screw and normally biased by the weight of said lever and segment away from contact with said screw, a spring latch carried by said lever, a socket member fixed to said carriage and with which said latch cooperates to hold said segment in screw-engaging position, a fixed stop, a member movably carried by said carriage in position to impinge on said stop as said carriage approaches a limit of traverse to be moved relative to said carriage as said carriage moves after such impingement, a latch release rod slidable in said socket member, and connections between said member and rod to cause such relative movement between said carriage and member to project said rod against and release said latch from said socket.

4. In combination, a traversing carriage, a rotary lead screw, a lever fulcrumed on an axis substantially parallel to said lead screw and held against motion axially thereof, a nut segment carried by said lever for engagement with said lead screw and normally biased by the weight of said lever and segment away from contact with said screw, a spring latch carried by said lever, a socket member fixed to said carriage and with which said latch cooperates to hold said segment in screw-engaging position, a fixed stop, a member movably carried by said carriage in position to impinge on said stop as said carriage ap-

proaches a limit of traverse to be moved relative to said carriage as said carriage moves after such impingement, a latch release rod slidable in said socket member, connections between said member and rod to cause such relative movement between said carriage and member to project said rod against and release said latch from said socket, and means actuatable to render said connections inoperative.

5. In combination, a traversing carriage, a rotary lead screw, a nut segment carried by said carriage and movable into and out of operative engagement with said screw and biased out of such engagement, a latch effective to retain said nut in operative position relative to said screw, a fixed stop, a member movably carried by said carriage in position to impinge on said stop as said carriage approaches a traversing limit to be stopped while said carriage continues its motion, a latch release mechanism cooperating with said member to cause such continuing motion of said carriage to release said latch, and means for moving said release mechanism into and out of cooperative relation to said member.

6. In combination, a traversing carriage, a rotary lead screw, a nut segment carried by said carriage and movable into and out of operative engagement with said screw and biased out of such engagement, a latch effective to retain said nut in operative position relative to said screw, a fixed stop, a member movably carried by said carriage in position to impinge on said stop as said carriage approaches a traversing limit to be stopped while said carriage continues its motion, a latch socket member, a latch release pin movably carried by said socket member, and means pivoted coaxially with said release pin for actuating said latch pin to release said latch, and rockable about its pivot into and out of cooperative relation to said movable carriage member.

7. In combination, a traversing carriage, a rotary lead screw, a nut segment carried by said carriage and movable into and out of operative engagement with said screw and biased out of such engagement, a latch effective to retain said nut in operative position relative to said screw, a fixed stop, a member movably carried by said carriage in position to impinge on said stop as said carriage approaches a traversing limit to be stopped while said carriage continues its motion, a head on said member, means including an element having a slot engageable over a portion of said member and cooperating with said head to release said latch by the continued motion of said carriage after the motion therewith of said member has been stopped, and means for moving said slotted element into or out of co-operation with said member.

8. In combination, a traversing carriage, a rotary lead screw, a nut segment carried by said carriage and movable into and out of operative engagement with said screw and biased out of such engagement, a latch effective to retain said nut in operative position relative to said screw, a fixed stop, a member movably carried by said carriage in position to impinge on said stop as said carriage approaches a traversing limit to be stopped while said carriage continues its motion, a latch socket member, a latch release pin movably carried by said socket member, a support rockable on an axis concentric with said release pin, said axis lying substantially parallel to the direction of carriage traverse, and a lever fulcrumed on said support transverse to said

axis, said lever having a part engageable with said latch release pin and a part having a slot movable on rocking of said support into or out of operative engagement with said movable member.

9. In combination, a traversing carriage, a rotary lead screw, a nut segment carried by said carriage and movable into and out of operative engagement with said screw and biased out of such engagement, a latch effective to retain said nut in operative position relative to said screw, a fixed stop, a member movably carried by said carriage in position to impinge on said stop as said carriage approaches a traversing limit to be stopped while said carriage continues its motion, a latch socket member, a latch release pin movably carried by said socket member, a support rockable on an axis concentric with said release pin, said axis lying substantially parallel to the direction of carriage traverse, and a lever fulcrumed on said support transverse to said axis, said lever having a part engageable with said latch release pin and a part having a slot movable on rocking of said support into or out of operative engagement with said movable member, said slotted part and said member having portions coacting to releasably latch said support in operative angular position.

10. In combination, a traversing carriage, a rotary lead screw, a nut segment carried by said carriage and movable into and out of operative engagement with said screw and biased out of such engagement, a latch effective to retain said nut in operative position relative to said screw, a fixed stop, a member movably carried by said carriage in position to impinge on said stop as said carriage approaches a traversing limit to be stopped while said carriage continues its motion, a latch socket member, a latch release pin movably carried by said socket member, a support rockable on an axis concentric with said release pin, said axis lying substantially parallel to the direction of carriage traverse, and a lever fulcrumed on said support transverse to said axis, said lever having a part engageable with said latch release pin and a part having a slot movable on rocking of said support into or out of operative engagement with said movable member, said slotted part and said member having complementally beveled engaging latch faces releasably holding said support in operative angular position.

11. In combination with a traversing carriage and a plurality of means for selectively producing traverse of said carriage, of a stop, a member movably mounted on said carriage for impingement on said stop, and means actuated on the further motion of said carriage after such impingement for rendering inoperative the selected traverse-producing means.

12. In combination with a traversing carriage and a plurality of means for selectively producing traverse of said carriage, one of said means comprising a lead screw and a nut element engageable with said lead screw, of a stop, a member movably carried by said carriage for impingement on said stop, and means actuated on the further motion of said carriage after such impingement has occurred for rendering inoperative the selected traverse-producing means, said inoperative rendering means acting when said lead screw and nut-traversing means is selected to produce such inoperativeness by disconnection of said nut from said lead screw.

13. In combination with a traversing carriage, a plurality of means for selectively producing traverse of said carriage, a latch for each such means for holding its respective means in operative condition, and means biasing each of said traverse-producing means to inoperative condition, of a stop, a member movably mounted on said carriage for impingement on said stop as said carriage is traversed and means actuated by continued movement of said carriage after such impingement to release said latches.

14. In combination with a traversing carriage, a plurality of means for selectively producing traverse of said carriage, one of said means comprising a lead screw and a nut element engageable with said lead screw, a latch for each such means for holding its respective means in operative condition, and means biasing each of said traverse-producing means to inoperative condition, said biasing means for said lead screw and nut element tending to separate said element from said screw, of a stop, a member movably mounted on said carriage for impingement on said stop as said carriage is traversed, and means actuated by continued movement of said carriage after such impingement to release said latches.

15. In combination with a traversing carriage, a plurality of means for selectively producing traverse of said carriage, one of said means comprising a lead screw and a nut element engageable with said lead screw, a latch for each such means for holding its respective means in operative condition, and means biasing each of said traverse-producing means to inoperative condition, said biasing means for said lead screw and nut element tending to separate said element from said screw, of a stop, a member movably mounted on said carriage for impingement on said stop as said carriage is traversed, means actuated by continued movement of said carriage after such impingement to release said latches, and means for operatively connecting or disconnecting said one traversing means to or from said movable member.

JOHN E. LOVELY.
